HUNTING JACKET

Harry E. Pocock, Snyder, N. Y., assignor to
Lyon & Coulson, Inc., Buffalo, N. Y.

Application December 16, 1939, Serial No. 309,617

4 Claims. (Cl. 2—94)

This invention relates to garments and particularly to jackets or coats such as are worn by sportsmen and hunters.

It has heretofore been proposed to associate with a jacket of the kind frequently worn by hunters, fishermen, and other sportsmen, a game pocket. Such pockets have frequently been disposed at the back of the jacket or coat to avoid, so far as possible, interference with the manipulation of hunting and fishing paraphernalia and for other reasons. One objection to prior art devices of this nature has been the fact that the presence of the rear pocket, pouch or pack has rendered the garment to some extent unsuitable for other uses, either by reason of the fact that the pocket, pouch or pack has been permanently associated with the garment or because its mode of association has so modified the garment as in and of itself to render the garment unsuitable or inconvenient for other uses. A further objection to devices of this nature found in the prior art has to do with inconvenience of use and discomfort to which the user is subjected by the presence of the game pocket, particularly when it contains articles whose weight tends to distort the coat or jacket and constrain his freedom of movement.

In the present invention I have devised a hunting jacket and game pouch combination wherein the game pouch itself may be quickly and conveniently removed from or secured to the rear side of the jacket. The mode of association of the game pouch with the jacket, when these component parts are manufactured in accordance with my invention, is such that the pouch itself is supported upon the jacket in a manner which does not distort or exert any undue pull on the jacket proper. This is of special benefit and desirability when the pouch contains articles of some weight in the nature of game or sporting paraphernalia. Further, the arrangement of the game pouch and its association with the hunting jacket is such as not to hamper or constrain free movement of body and limb of the wearer of the jacket, and the pouch itself is arranged to give convenient and varying degree of access to its interior.

In arranging the hunting jacket and associated game pouch in accordance with the teachings of this invention, the pouch is secured to the jacket at spaced points on what might be referred to as the structural framework of the hunting jacket, considering the shoulder seams and belt or waist of such jacket as analogous to a structural framework. Other advantages of

manufacture and use from the standpoint of convenience, economy, and all-around adaptability will appear from a consideration of the ensuing specification and the accompanying drawing.

In the drawing:

Fig. 1 is a rear view of a hunting jacket being worn by a user and having associated therewith the game pouch which, in combination with the jacket, forms the subject matter of this invention.

Fig. 2 is an elevational view of the reverse side of the game pouch to that which appears in Fig. 1, and

Fig. 3 is a fragmentary cross-sectional view through the shoulder seam of the hunting jacket showing one of the securing devices.

In the drawing like characters of reference denote like parts and the numeral 10 refers generally to a hunting jacket which in details of construction other than those referred to herein is conventional and may be varied as desired. As seen in Fig. 1, the jacket 10 is preferably of the kind which embodies a belt or waist reinforcing band 11. The game pouch itself, designated generally 12, involves a pocket portion 13 which is closed at its upper end as by the seam 14 and has associated therewith an upwardly extending panel portion 15 which terminates upwardly in diverging tab portions 16, each of which is provided with a pair of buttonholes 17 for securing to buttons 18 which are secured to the jacket 10 along the shoulder seam 19 thereof, as shown in detail in Fig. 3.

The tab portions 16 are preferably reinforced in the region of the buttonholes 17 as by the inserts 20.

As has been stated, the pocket portion 13 is closed at its upper edge by the seam 14 and access to the interior thereof is had by way of openings at opposite sides of the pocket which openings extend from the seam 14 downwardly along the outwardly flaring side edges of the pocket portion 13 to substantially the point marked A in Fig. 2. Buttons 24 are provided at opposite sides of the back of the coat, preferably along the waist reinforcement 11 thereof for engagement by buttonholes 25 formed in both the inner and outer or front and back panel portions which form the pocket 13.

It will be noted that the buttonholes 25 are disposed somewhat above the lower extremities of the side openings and only the inside or front panel of the pocket 13 may be secured to the button 24 or both the inside and outside or front and

back panels may be secured to the button, as desired. In the latter case greater capacity of the pocket is attained and greater security against losing its contents with the sacrifice of a certain degree of readiness of accessibility to the pocket. In use the outer or back panel of the pocket 13 may be momentarily unbuttoned from the jacket and from the front or inside panel portion of the pocket to facilitate the insertion or removal of articles into or out of the pocket. It is preferred that the opposed panel portions which form the pocket 13 be reinforced on both their sides in the region of the buttonholes 25 as indicated at 26.

In the illustrated embodiment the interior of the pocket portion 13 is provided with a rubberized or otherwise waterproofed lining, as at 27, which will serve to protect the contents of the pouch against access of moisture from without but which is primarily provided for the protection of the wearer of the jacket and pouch against contamination by game contained in the pocket portion of the pouch. The lining 27 also facilitates cleaning the interior of the pocket portion after use.

The pouch unit of the present invention may be conveniently formed from a single main body piece which has a portion of the full outline of the pouch as illustrated in Fig. 2, plus a lower extension which is folded upon such portion and stitched thereto as at 14 to form the pocket portion of the pouch. The edges of the pouch are hemmed or reinforced in a conventional way and the waterproof lining is secured to the main body portion prior to the folding of the lower extension to form the pocket 13. The portion which is folded upon itself to form the pocket 13 is then stitched to the main body portion from the folded portion at the lower edge of Fig. 2 to the points marked A along its opposite side edges, to complete the pocket portion of the pouch.

It is to be noted that the seam 14 is shown as being partially ripped in Fig. 2 with a portion of the front or inside panel of the pocket 13 folded over. This is for the purpose of illustration only and the upper edge of the two pocket panels are normally stitched together entirely across the seam 14.

The indentation or inwardly curving of the lateral sides of the pouch 12, which curving extends from the tab portions 16 substantially down to the point where the pouch is secured to the jacket at the waistline, permits free bodily movement and particularly free shoulder movement of the wearer without sacrificing the advantages which are gained by providing the widely spaced upper and lower securement of the pouch to the jacket.

It will appear to those pursuing the principles and teachings of this invention that certain modifications may be made without departing from the spirit or scope of the invention which is not to be considered as limited otherwise than in the appended claims.

What is claimed is:

1. The combination of a hunting jacket and removable game pouch, said jacket having pouch securing means adjacent its opposite shoulder portions and other pouch securing means laterally spaced and disposed at its lower portion, said pouch comprising a pocket portion having opposed panels secured to each other along their upper and lower horizontal edges and having side

openings for access to said pocket, said pouch having a panel portion extending upwardly from the upper edge of said pocket portion and having means for detachable engagement with the 5 securing means disposed at the opposite shoulder portions of said jacket, and means associated with said pouch for detachable engagement with the lower securing means of said jacket.

2. The combination of a hunting jacket and 10 removable game pouch, said jacket having pouch securing means adjacent its opposite shoulder portions and other pouch securing means laterally spaced and disposed along its waist line, said pouch comprising a pocket portion having 15 opposed panels secured to each other along their upper and lower horizontal edges and having side openings for access to said pocket, said pouch having a panel portion extending upwardly from the upper edge of said pocket portion and having 20 means for detachable engagement with the securing means disposed at the opposite shoulder portions of said jacket, and means associated with said pouch for detachable engagement with the securing means along the waist line of said 25 jacket.

3. The combination of a hunting jacket and game pouch, said jacket having pouch engaging means along its opposite shoulder seams and at points laterally spaced along its waistline, said 30 pouch comprising a lower pocket portion having opposed panels secured to each other along their upper and lower edges and along the lower portion of their lateral edges, the upper portion of said lateral edges being normally unsecured to 35 permit access to the interior of the pocket so formed, said pouch having a panel portion extending upwardly from said pocket portion and terminating upwardly in means for detachable engagement with the securing means disposed at the opposite shoulder portions of said jacket and means along the normally unsecured portions of the edges of each of said pocket panel 40 portions for independent and detachable engagement with the engaging means along the waist 45 line of said jacket.

4. The combination of a hunting jacket and game pouch, said jacket having pouch engaging means along its opposite shoulder seams and at points laterally spaced along its waistline, said 50 pouch comprising a lower pocket portion having opposed panels secured to each other along their upper and lower edges and along the lower portion of their lateral edges, the upper portion of said lateral edges being normally unsecured to 55 permit access to the interior of the pocket so formed, said pouch having a panel portion extending upwardly from said pocket portion and terminating upwardly in means for detachable engagement with the securing means disposed at the opposite shoulder portions of said jacket and means along the normally unsecured portions of the edges of each of said pocket panel 60 portions for independent and detachable engagement with the engaging means along the waist 65 line of said jacket, the portion of said pouch between said waistline engaging means and said shoulder engaging means being of substantially less width than said pocket portion and the width of said upwardly extending panel 70 portion at its upper edge.

HARRY E. POCOCK.
